SNAP-ON BOTTLE BASE

Philip A. Derham, Rosemont, Pa., assignor to Victor Metal Products Corporation, Brooklyn, N. Y., a corporation of New York

Application July 28, 1945, Serial No. 607,566

5 Claims. (Cl. 248—310)

1

This invention relates to bases for bottles or the like articles and particularly to that type of such bases as may be easily attached to and removed from the bottle.

The invention contemplates the provision of an inexpensive base readily moldable of plastic material and quickly and easily attached to the bottom of a glass bottle or the like article provided with a bead, by a twisting movement, and when so attached being firmly secured in place by the inherent resiliency thereof.

The invention further contemplates the provision of a moldable snap-on base provided with suitable holding lugs adapted removably to engage a cooperating bead at the bottom of a bottle or the like article, said base being provided with means to identify the bottle or its contents.

The invention further contemplates the provision of a flexible split base braced by means of an integral but flexible member and provided with two rows of alternating vertically spaced apart lugs between which rows the bead of a bottle or similar article may be inserted when the base is first slightly twisted and spread, the bracing member permitting such twisting because of its form and arrangement.

The various objects of the invention will become clear from the description which follows and from the drawings, in which,

Fig. 1 is a top plan view of the base.

Fig. 2 is a front elevation thereof partly in section and showing in dash-dot lines the position assumed by the bottle when assembled to the base.

Fig. 3 is a side elevation of the base in a twisted position such as that assumed thereby when the base is to be inserted into place or removed from the bead, showing how one part of the base may be separated from the other.

Fig. 4 is a fragmentary vertical section of the base taken on the line 4—4 of Fig. 1 showing in dash-dot lines part of the bottom of the bottle resting on one of the lugs of the lower row.

Fig. 5 is a similar section taken on the line 5—5 of Fig. 1 showing the holding lugs on an enlarged scale.

In the practical embodiment of the invention shown by way of example, the base 10 and all of its component parts are integrally molded of a single piece of suitable material such as synthetic plastic. The major part of the base comprises the annular part or rim 11 provided with the integral diametrically disposed brace 12, the lower surface 13 of which is preferably co-

2

planar with the lower surface of the rim, whereby a surface of substantial area is provided to rest on a support such as a display counter, table or the like. The brace 12 is preferably though not necessarily of rectangular cross section throughout, being comparatively wide and thin to provide wide upper and lower surfaces thereon. Consequently the brace may readily be bent, twisted or flexed when the entire base 10 is distorted without materially affecting the supporting function of the brace.

To permit the twisting above referred to, the rim 11 is split or severed at one point thereof arranged preferably midway between the ends 15 of the brace 12 to provide the free end faces 15, 16 thereon, which faces are normally in contact with each other due to the inherent resiliency of the rim and its tendency to contract. The lower part 17 of the rim is preferably thicker than the upper part 18 thereof, the bevelled or conical outer surface 19 connecting the outer cylindrical surfaces 20 and 21 of said lower and upper parts respectively. The common inner surface 22 of said parts 20 and 21 is preferably upright or cylindrical. However, the surface 22 is interrupted by two rows of holding lugs as 25 and 26 respectively.

As best seen in Fig. 5, the upper lugs 25 are integral with and project inwardly from the thinner upper part 18 of the rim and are made as thin as possible consistent with the function thereof, being of about the same thickness as that of the brace 12. While the upper faces of the lugs 25 are preferably coplanar with the upper face of the rim, the under faces 27 are preferably concave to fit the projecting convex bead 28 on the bottom of the bottle 29. The lugs 25 are spaced apart circumferentially of the rim a distance about equal to the circumferential length of the lower lugs 26 for ease in molding the lugs integrally with the rim.

Since the lower lugs 26 sustain the weight of the article to which the base is attached, said lugs are considerably higher or thicker than the upper lugs. The spacing between adjacent lower lugs is about equal to the circumferential lengths of the upper lugs, while the upper surfaces of the lugs 26 are concave to fit the under side of the bead 28. The lowermost surfaces 30 of the lower lugs are preferably coplanar with the lower surfaces of the rim and of the brace.

Upstanding from the rim 11 is the member 31 preferably of about the same thickness as that of the upper part 18 of the rim, and preferably shaped to fit the bottle or other article

29. Identifying ornamental or other matter as 32 may be imprinted upon or otherwise impressed into the outer surface of the member 31. Said member serves not only to carry such matter, but serves also as a stiffener to prevent undue distortion of the front or unsplit part of the rim. The upper and lower lugs may be omitted at points where excessive difficulty may be experienced in assembling the bottle with the base or in molding the lugs. For example, the lugs are preferably omitted across the width of the upstanding member 31.

It will now be seen that by twisting the base 10 out of its normal plane into approximately the position shown in Fig. 3, the end 16 of the rim is arranged in sufficient vertical spaced relation to the normally adjacent end 15 thereof to provide a space through which the bead 28 and the lower part of the bottle may be passed to a sufficient extent to arrange part of the bead at the less distorted front part of the rim and between the upper and lower rows of lugs thereon. The ends 15 and 16 of the base may now be spread laterally enough to carry the lower lugs past the upper part of the bead and into contact with the lower part of the bead or to make any other necessary adjustments to snap the base in place with the bead between and held by the upper and lower rows of lugs. Since the base is molded into an initial shape such as to fit the bead snugly, the base has an inherent resiliency tending to restore it to its original shape and to maintain it in that shape. Hence the base snugly fits and holds the bead until deliberately removed therefrom.

Removal is readily effected by reversing the operation above described, that is, by merely twisting the base off the bead. It will be seen that I have provided an inexpensive ornamental identifying base easily molded in one piece, easily attached to and detached from the beaded bottom of an article to which attachment of bases is otherwise difficult, which base, after attachment, is securely self-held in place. It will also be seen that various obvious changes may be made in form, dimensions and arrangement of the parts without departing from the spirit of the invention defined in the appended claims.

I claim:

1. A flexible one piece base for a bottle or the like having a lowermost bead thereon comprising a flexible annular rim, a flexible brace integrally connecting diametrically opposite parts of the rim and arranged with its lower surface substantially coplanar with the lower surface of the rim, the brace being laterally distortable out of its normal plane, the brace determining the maximum distance between said diametrically opposed parts while permitting the parts of the rim on one side of the brace to be twisted laterally out of the normal positions thereof in which the bead is overhung by the rim, that part of

the rim on the other side of the brace being maintained by the brace against substantial change in size and shape, a series of equally spaced lugs projecting inwardly from the upper 5 part of the rim and having square corner edges thereon, a second series of equally spaced lugs projecting inwardly from the lower part of the rim and having square corner edges thereon, each of the lugs of the second series being of 10 greater height than the height of the upper lugs and being arranged between and below a pair of the upper lugs to form a recess therebetween for the reception of the bead, the rim on one side of the brace being severed to form free ends 15 thereon at a point substantially midway between the ends of the brace.

2. A flexible snap-on base for a beaded article comprising a split flexible annular rim provided with two rows of inwardly projecting and vertically spaced apart rows of lugs arranged in alternating relation and a flexible brace integral with the rim holding diametrically opposite parts of the rim together against change in diameter and shape except for a limited amount of vertical distortion.

3. A base according to claim 2 in which the rim part opposite the split is devoid of lugs and is instead provided with an upstanding member projecting above the rim more than twice the 30 height of the rim and of sufficient area to have decorative and identifying matter placed thereon, and of substantially the same thickness as that of the upper part of the rim.

4. A base according to claim 2 in which the rim 35 is of uniform height, the thickness of the brace is substantially the same as the height of the upper row of lugs and less than the height of the lower row of lugs, and the corner edges of the lugs are sharp.

5. A base according to claim 2 in which the rim, brace and lugs are molded in one piece of plastic material, the rim being provided with an upstanding member of greater height than that of the rim, of greater width than the width of the 45 brace and of substantially the same thickness as that of the brace, the thickness of the brace being a small fraction of the width of the brace, and the width being approximately that of a lug adjacent thereto, whereby the rim and brace are laterally distortable and must be laterally distorted when the bead of the article is being inserted between the rows of lugs.
